WELLHEAD

John E. Eckel, Houston, Tex., assignor to Oil
Center Tool Company, Houston, Tex., a corpo-
ration of Texas

Application April 16, 1948, Serial No. 21,384

3 Claims. (Cl. 166—14)

1 This invention relates to a well head.

The present application is a continuation-in-part of co-pending application Serial No. 660,208 filed by applicant and Fritz Richard on April 6, 1946.

An object of the invention is to provide a novel type of sealing assembly between upper and lower tubular members of a well head.

It is a further object of the present invention to provide in a well head assembly embodying a casing head and a tubing head mounted thereon and secured thereto, a novel type of seal between the upper end of the casing, supported by the casing head and the base of the tubing head, said sealing means being of such construction that the seal ring, or packing, therein will be compressed when the heads are drawn together by the securing means such as bolts connecting the flanges of the heads.

It is a further object of the present invention to provide a novel type of sealing assembly which may be installed, or removed, as a unit and which is designed to form a seal between the base of the tubing head and the upper end of a casing which is supported from the casing head and extended up into the tubing head.

It is a still further object of the invention to provide in a well head, a sealing assembly designed to form a seal between the upper end of the well casing and the tubing head which is of such construction that it may be readily removed or installed by means available at the location where the well head is in use.

Other objects and advantages will be apparent from the following specification which is illustrated by the accompanying drawings, wherein:

Figure 1 is a side elevation of a well head shown partly in section and embodying the invention and,

Figure 2 is a cross-sectional view taken on the line 2—2 of Figure 1.

Referring more particularly to the drawings the numeral 1 designates a casing head.

Supported on the casing head there is a tubing head 2.

The heads 1 and 2 are of tubular formation and their adjacent ends have external registering flanges which may be secured together in any preferred manner. As shown they are secured together by a series of bolts 3 having clamp nuts screwed onto their respective ends to draw the heads together.

As illustrated in Figure 1 the casing head has an inside downwardly tapering seat 4 whereon the tubular casing hanger 5, which tapers downwardly externally, is seated.

2 The well casing 6, in the present illustration is supported from said hanger. In the present illustration the hanger 5 has external countersunk seal rings 7 therein to form seals with the seat 4.

In this type of well head the base, or lower end, of the tubing head is internally counterbored and the upper end of the casing 6 extends up into the tubing head.

10 Within the counterbore of the tubing head there is a sealing assembly which comprises an upper annular junk ring 8, an intermediate seal ring 9, formed of rubber or other sealing material, and a lower annular compression ring 10 15 which is flared outwardly and downwardly and rests on the upper end of the hanger or other casing supporting means beneath.

This compression ring 10 has an external annular groove 11 therearound and secured to the tubing head 4 and extending radially inwardly there is a locking ring 12 whose inner margin projects into said groove. This ring 12 may be secured to the tubing head by means of set screws, as 13, and suitable openings 14 are provided in the flared portion of the compression ring for the insertion of a screw driver to insert or remove the screws 13 in assembling the sealing assembly.

The locking ring 12 may be formed of sections, 20 if desired, for easy insertion and removal.

When the locking ring 12 is installed its inner margin will project into the groove 11, as above indicated, and will maintain the sealing assembly in its proper position in the tubing head. As 35 shown in the drawing, the thickness of the locking ring 12 is less than the width of the groove 11 so that after the assembly is made, as illustrated in Figure 1, a limited independent upward movement of the compression ring with respect to the 40 locking ring may occur.

As hereinabove stated the lower end of the tubing head is internally counterbored thus providing an internal downwardly facing shoulder 15 in the tubing head against which the junk 45 ring abuts to limit its upper movement.

The upper end of the junk ring 8 is reduced externally in diameter and fits up within the tubing head above the shoulder 15 and its upper end is upwardly and outwardly flared forming a 50 guide 16 for guiding the drill bit when it is desired to lower the drill through the head.

In mounting the sealing assembly within the tubing head the junk ring 8 and seal ring 9 are inserted within the counterbore; thereafter, the 55 sectional locking ring 12 is placed within the groove 11 of the compression ring and these parts

are moved into place within the counterbore. The screws 13 are then threaded into the tubing head with this operation being carried out through the openings 14 in the flared lower end of the compression ring. After the locking ring 12 is in position, it is evident that the sealing assembly is held against downward displacement from the counterbore by means of said locking ring; however, because the thickness of the ring is less than the width of the groove 11, the compression ring may undergo limited axial movement with respect to the locking ring. Therefore, when the tubing head is assembled on the casing head, the lower end of the compression ring engages the hanger 5 and an upward compressive force is applied to the sealing ring.

It is usually desirable to test the seals before the well is brought in. Means providing for this test is illustrated in Figure 1 wherein the tubing head is provided with a test port 17 leading into the chamber 18 between the upper seal ring 9 and the lower seals between the casing hanger and the tubing head, said test port having a connection 19 screwed into the outer end thereof. In making the test a pressure hose may be connected to the connection 19 and pressure fluid, such as oil, introduced into the chamber 18. While this is being done the plug 20 should be removed from a bleeder port 21, leading from the chamber 18 to permit the escape of all air from the chamber 18 and the said plug should then be replaced and pressure applied to the liquid filling the chamber 18. This pressure line should be equipped with a pressure gauge and if the upper or lower seals leak it will be indicated by the gauge. If after the test is made the gauge does not indicate leakage of the seals the well can then be brought in.

The drawings and description are illustrative merely while the broad principle of the invention will be defined by the appended claims.

What I claim is:

1. In a tubular head having a recess in its lower portion and having a well casing extending upwardly into the bore of the head opposite said recess a packing assembly for sealing about a casing and adapted to be located within the recess, said assembly comprising, a compression ring having an external groove, a seal ring formed of resilient material on said compression ring, a locking ring extending radially inwardly into said groove and having a thickness less than

the width of the groove, means for securing said locking ring to the head, whereby the packing assembly is retained against displacement from the lower end of the head, said compression ring being downwardly flared and being provided with an opening for access to said securing means.

2. In a tubular well head a packing assembly for sealing about a casing extended into the head, said assembly comprising, a compression ring having an external groove, a seal ring formed of resilient material on said compression ring, a locking ring secured to the head and extending radially inwardly into said groove, a junk ring around the upper end of the casing and mounted on the seal ring and interlocked with the head against upward movement with said head, the upper end of the junk ring overlying the upper end of the casing extending through the head and being outwardly flared to form a drill bit guide.

3. In a tubular well head having a counterbored recess in its lower end, a packing assembly including a metallic ring interlocked with the upper portion of the recess, a sealing ring below the metallic ring and adapted to seal with a casing extending into the lower portion of the head, a compression ring within the recess below the sealing ring and having an external groove intermediate its upper and lower ends, a locking ring engaged within the external groove and adapted to be detachably fastened to the body of the head to retain the compression ring, means fastening the locking ring to the body of the head sealing ring and metallic ring in position within the recess in the head, the lower portion of the compression ring being flared outwardly in overlying relationship to the locking ring with said flared portion having access openings therein whereby the fastening means for said locking rings are accessible from below the assembly.
